Patented Oct. 19, 1965

202,556

CASE FOR AN ELECTRICAL INSTRUMENT, OR THE LIKE

Richard W. Seabury, Jr., Towaco, N.J., assignor to Radio Frequency Laboratories, Inc., Boonton, N.J., a corporation of New Jersey

Filed May 15, 1964, Ser. No. 79,997

Term of patent 14 years

(Cl. D26—5)

FIG.-2-

FIG.-3-

FIG.-1-

FIG.-4-

FIG.-5-

FIGURE 1 is an isometric view showing the front and left side of a case for an electrical instrument or the like embodying my new design;

FIGURE 2 is an elevational view showing the right side thereof;

FIGURE 3 is an elevational view showing the back thereof;

FIGURE 4 is an elevational view showing the bottom thereof; and

FIGURE 5 is an isometric view corresponding to FIGURE 1 and showing the handle rotated to a forward position and the case sides in open positions.

The dominant features of my new design reside in the portions shown in full lines.

I claim:

The ornamental design for a case for an electrical instrument or the like, as shown and described.
